DESIGN FOR FANCY PAPER OR SIMILAR ARTICLE

Norman E. Scott, Atlantic, Mass., assignor to
Deerfield Glassine Company, Inc., Monroe
Bridge, Mass., a corporation

Application April 24, 1935, Serial No. 56,526

Term of patent 3½ years

To all whom it may concern:

Be it known that Norman E. Scott, a citizen of the United States, residing at Atlantic, in the county of Suffolk and State of Massachusetts, has invented a new, original, and ornamental Design for Fancy Paper or Similar Article, of which the following is a specification.

In the accompanying drawing:—

The figure is a surface view of a piece of fancy

paper or similar article showing the design. The area within the square ACDB represents one complete unit of the design.

I claim:—

The ornamental design for fancy paper or similar article as shown and described.

In testimony whereof I affix my signature.

NORMAN E. SCOTT.
